UNITED STATES PATENT OFFICE.

ERASTUS W. ROGERS, OF DURHAM, NORTH CAROLINA.

STOVE.

Application filed May 1, 1926, Serial No. 106,043. Renewed March 20, 1928.

This invention relates to stoves and other heating devices and has for its principal object the provision of means for the efficient utilization of the heat of the products of combustion after they leave the fire pot, for cooking or general heating purposes.

Another object of the invention is to provide flue-means in communication with the fire pot of a stove or other source of combustion, said means being arranged to form a compartment whereby the heat from said means is concentrated within the air space of said compartment.

A further object of the invention is the provision of a heating device forming jacketed compartments with flues arranged in said jacket communicating with the combustion chamber of the heating device for directing the flow of the products of combustion into heat interchanging relationship with the walls of said compartments, and being provided with dampers for selectively diverting the flow of combustion products for the purpose of heating certain compartments or parts thereof to a greater or less extent, or to improve the draft by conducting the products of combustion directly to the chimney pipe.

Still another object of the invention resides in the construction of heating apparatus of the class described which may, if desired, be used as an attachment to stoves already built, or incorporated into stoves, ranges, furnaces or the like at the time of their construction, ease of installation, and accessibility for the purpose of cleaning.

Other objects of the invention will appear as the following description of a preferred embodiment thereof proceeds.

In the drawings:—

Figure 1 is a perspective view, part being broken away, of a stove embodying the principles of my invention.

Figure 2 is a section taken along the line 2—2 of Figure 1.

Figure 3 is a section taken along the line 3—3 of Figure 1.

Figure 4 is a section taken along the line 4—4 of Figure 1.

Figure 5 is a section taken along the line 5—5 of Figure 1.

Figure 6 is a perspective view showing a modified form of the invention.

Referring now in detail to the several figures, the numeral 1 represents in general, a stove having the fire pot 2, feed door 3, ash pit 4 and ash tray 5, the latter being prefer-

ably provided with a draft damper 6. The stove preferably is supported upon legs 7 at a distance from the floor. The parts which have just been described are common to any 60 stove and no claim is made to them as part of the present invention, except where necessarily combined with the structure now to be defined.

The fire pot is preferably extended laterally as shown at 8 and 9 in Figure 2, the lateral extensions being formed with flanged openings 10 and 11 to receive the flue casing 12. This casing is in general of an inverted U-shape having vertical limbs 13 and 14 fitting down upon the flanged openings 10 and 11, and joined by a top transverse member 15 and preferably by an intermediate transverse member 16. The flue casing may be made in upper and lower sections as shown, 75 in which event the intermediate transverse members 16 are provided with flanged openings 17 and 18 upon which the upper section of the casing is fitted.

The vertical limbs and transverse members are double-walled as shown, and provided inside with partitions, as follows, forming flues. The vertical limbs 13 and 14 in those parts which lie between the stove and the intermediate transverse member are formed as single conduits through which the products of combustion from the fire pot pass upward. At the level of the bottom of the intermediate transverse member, a horizontal partition 19 is provided in each of the 90 vertical limbs extending part way across said limbs and joining a vertical partition 20 which extends to the top transverse member and part way across the same, the partitions 20 being discontinuous adjacent the middle 95 of the top transverse member affording an avenue of communication between the space within the forward part of the top transverse member and the space within the rear part of said member, which latter space is in communication with the flues 21 formed by the partitions 19 and 20 at the rear of the vertical limbs. Said flues are in open communication with the space within the intermediate transverse member through openings 22. By 100 means of this arrangement of flues, the hot products of combustion rise to the top of the vertical limbs through the forward flues 20' without normally having access to the intermediate transverse chamber, and then, 105 passing through the space between the partitions 20 in the top transverse member, said

products of combustion flow downwardly through the flues 21 and into the intermediate transverse member, being discharged from the same through the chimney pipe 23 after 5 passing around the distributing baffles 40.

The vertical limbs of the flue casing, together with the top of the stove, intermediate transverse member, and top transverse member together, form compartments 24 and 10 25 surrounded on their top, bottom, and sides by the extensive heat conductive surfaces formed by the top of the stove and the flue casing. It is clear that the heat of the products of combustion, which usually pass 15 directly into the chimney pipe and are wasted, are, in the present construction, concentrated within the compartments 24 and 25 intensely heating the air therein contained and assisting in cooking whatever objects may be arranged in said compartments for that purpose.

By the novel arrangement of the partitions which I have above described, the flow of products of combustion is so regulated 25 that the hottest gases contact with the sides of the compartments and with the top of the uppermost compartment, the top of the stove being in heat conductive relation to the lower compartment. In this manner both compartments are substantially equally heated. It 30 may be desirable, however, at certain times to regulate the heat so as to divert the maximum heat to the intermediate transverse member. This is done by means of dampers 35 26 and 27 controlling openings which lead from the front flues 20' of the intermediate transverse member. When these dampers are opened the combustion products are conducted directly to the intermediate transverse 40 member and drawn directly out through the smoke pipe 23. This arrangement is of especial advantage when the upper compartment 24 is being used as an oven. It may happen that the upper part of said oven becomes 45 duly heated. The dampers 26 and 27 may then be opened diverting the heat to the lower part of the oven. Opening the dampers has the effect also of providing a direct path for the combustion products from the 50 fire pot to the smoke pipe, thus improving the draft of the heating device. This is particularly advantageous when starting a fire or when attempting to burn up a slow fire.

For convenience in cleaning out soot from 55 the lateral extensions of the fire pot and from the transverse members 15 and 16, I have provided the removable lids 28, 29 and 30. The lid 28 preferably is flanged on all four edges and fits down over the open end of the upper 60 section of the flue casing. The other lids are preferably flanged only on their front and back edges as shown at 31 and 32 in Figure 1, and rest upon horizontal flanges 33 provided at the edges of the respective sections with 65 which they are associated. The cover 30,

which lies above the fire pot, is provided with the usual stove lid 34.

In the example of my invention shown the cover 30 is interchangeable with the cover 29.

In that form of my invention shown in Figure 1 the stove has been provided, mainly for the sake of design, with hollow pillars 35 and 36 below the vertical limbs of the flue casing, closed from said casing but in line therewith. These pillars are supported upon the upper wall of the ash pit 5, which has been extended laterally on both sides to meet said pillars. This disposition of the ash pit walls makes it possible to use an ash tray of greater capacity than would otherwise be possible so that it is not necessary to remove ashes from the stove as frequently as is ordinarily required. The spaces between the vertical pillars 35 and 36 and the side walls of the fire pot may serve 80 conveniently as warming ovens.

In that form of my invention shown in Figure 6 there is no intermediate transverse member, so that the partitions within the flues may be dispensed with. In this embodiment of my invention the flue casing 37 may be added as an attachment to a stove already built, and for this purpose it is preferable that the casing include the bottom transverse member 38 which in the form of my invention first described is part of the fire pot. The lower face of the bottom transverse member 38 is suitably apertured to fit down upon that part of the stove with which it is to be associated, and the furnace pipe represented by the reference numeral 39 leads from the lower face of the top transverse member.

While I have in the above description disclosed what I believe to be a preferred and practical embodiment of my invention, it is to be understood that the specific details described are not limitative in their effect upon the invention but merely illustrative except in so far as they are expressly prescribed by the terms of the appended claims.

Having described my invention what I claim as new and desire to secure by Letters Patent, is:—

1. A heating device including a fire pot having lateral openings, a casing comprising superposable sections each including lateral branches and a transverse connecting member, the lower section fitting said openings and the upper section fitting suitable openings in said lower section, the transverse connecting member of said lower section being provided with a connection for a smoke pipe for drawing products of combustion from said fire pot through said casing thereby concentrating heat within the spaces bounded by said branches and transverse members, and means within said casing for directing the flow of products of combustion serially first through said upper transverse member and then through the transverse member of the lower section.

2. A heating device including a fire pot having lateral openings, a casing comprising superposed sections each including lateral branches and a transverse connecting member, the lower section fitting said openings and the upper section fitting suitable openings in said lower section, the transverse connecting member in said lower section being provided with a connection for a smoke pipe for drawing products of combustion from said fire pot through said casing thereby concentrating heat within the spaces bounded by said branches and transverse members, means within said casing for directing the flow of products of combustion serially first through said upper transverse member and then through the transverse member of the lower section, and baffles in said transverse members for uniformly distributing the flow of combustion products through said members. 75

3. A heating device including a fire pot having lateral openings, a casing comprising superposed sections each including lateral branches and a transverse connecting member, the lower section fitting said openings and the upper section fitting suitable openings in said lower section, the transverse connecting member of said lower section being provided with a connection for a smoke pipe for drawing products of combustion from said fire pot through said casing thereby concentrating heat within the spaces bounded by said branches and transverse members, means within said casing for directing the flow of products of combustion serially first through said upper transverse member and then through the transverse member of the lower section, and dampers controlled at will for admitting combustion products direct from said branches to the intermediate transverse connecting member. 80

4. A heating device comprising a fire pot having lateral openings, a casing including branches communicating with said openings and having top and intermediate transverse connecting members, said intermediate connecting member being provided with a connection for a smoke pipe for drawing products of combustion from said fire pot through said casing thereby concentrating heat within the spaces bounded by said branches and transverse members, and means within said casing for directing the flow of products of combustion serially first through said upper transverse member and then through said intermediate transverse member, dampers controlled at will for admitting the combustion products direct from said branches to the intermediate transverse connecting member, and removable covers giving access to said transverse members. 85

5. A heating device comprising a fire pot having lateral openings, a casing including branches communicating with said openings and having top and intermediate transverse connecting members, said intermediate connecting member being provided with a connection for a smoke pipe for drawing products of combustion from said fire pot through said casing thereby concentrating heat within the spaces bounded by said branches and transverse members, means within said casing for directing the flow of products of combustion serially first through said upper transverse member and then through said intermediate transverse member, and baffles in said transverse members for uniformly distributing the flow of combustion products through said members. 90

6. A heating device comprising a fire pot having lateral openings, a casing including branches communicating with said openings and having top and intermediate transverse connecting members, said intermediate connecting member being provided with a connection for a smoke pipe for drawing products of combustion from said fire pot through said casing thereby concentrating heat within the spaces bounded by said branches and transverse members, means within said casing for directing the flow of products of combustion serially first through said upper transverse member and then through said intermediate transverse member, and dampers controlled at will for admitting combustion products direct from said branches to the intermediate transverse connecting member. 95

7. A heating device comprising a fire pot having lateral openings, a casing including branches communicating with said openings and having top and intermediate transverse connecting members, said intermediate connecting member being provided with a connection for a smoke pipe for drawing products of combustion from said fire pot through said casing thereby concentrating heat within the spaces bounded by said branches and transverse members, means within said casing for directing the flow of products of combustion serially first through said upper transverse member and then through said intermediate transverse member, dampers controlled at will for admitting the combustion products direct from said branches to the intermediate transverse connecting member, and removable covers giving access to said transverse members. 100
